UNITED STATES PATENT OFFICE.

MICHAEL J. MCANENY, OF DENVER, COLORADO, ASSIGNOR OF ONE-HALF TO E. N. STROM, OF CHICAGO, ILLINOIS.

WATER-CLOSET BOWL.

Application filed October 18, 1922. Serial No. 595,337.

To all whom it may concern:

Be it known that I, MICHAEL J. MCANENY, a citizen of the United States, residing at Denver, in the county of Denver and State 5 of Colorado, have invented a new and useful Improvement in Water-Closet Bowls, of which the following is a specification.

My invention relates to an improvement in water-closet bowls, and it is fully described and explained in the specification and illustrated in the accompanying drawing, in which:

Figure 1 is a plan view of the bowl, and Figure 2 is a section on line 2—2, Fig. 1.

15 The bowl 3, of any of the usual general forms, is provided around its upper edge with a circumferential hollow rim 4 pref-erably closed about the bowl, except for a vent-opening shown to be provided at 5, 20 and opening at the rear of the bowl, into a chamber 6 at opposite sides of an inclined valve-seat 7 formed in its forward wall and upon which a flap-valve 8 is hinged for controlling the discharge of water into the 25 bowl. A vented cylinder 9 extends through the top of the chamber 6 and contains a spring-pressed piston 10 having its pendent stem 11 connected at 12^a by a link 12 with a lever 13 fulcrumed at one end to the rear 30 wall of the chamber and extending at its opposite end to a catch 14 rising from the base of the seat 7 to be engaged, for re-leasably locking the valve, by a dog 15 piv- 35 oted on its rear face. The usual seat is rep-resented at 16.

With the bowl in position for use, the flushing water enters the chamber 6 through a pipe 17, which may lead directly from the source of water-supply under any de- 40 gree of pressure which may be the normal city pressure, or any pressure from one pound to a hundred pounds or more, per square inch, in which case a suitable valve (not shown), but which should be spring- 45 closed, would be provided in the pipe in position relative to the seat 16 for convenient access for manipulation by the user; or the pipe may lead from the more usually-provided valve-controlled rear or overhead 50 flush-tank.

Admission of water through the pipe 17 fills the rim 4 and chamber 6, the combined reservoir-capacities of which need not, for the flushing purpose, exceed materially if

at all, about two gallons of water. With the 55 chamber 6 filled, the resultant pressure of the water therein raises the piston 10 to trip the dog 15 and unlock the valve 8 to permit the contents of the chamber and rim to gush into and flush the bowl, whereupon 60 the spring-pressure against the piston 10 re-stores the lever 13 to its normal position for the dog-tripping purpose, and the valve 8 will close by gravity against its seat and become locked by the dog 15 riding over 65 the catch 14 to the condition illustrated. Until the water-supply through the pipe 17 becomes arrested by closure of the afore-said valve controlling the same, there may be a more or less slight after-flow of water 70 into the chamber 6 during its evacuation, de-pending on the time it takes for that valve to close; but the quantity of such after-flow should be negligible in the way of increasing the amount of actual flushing water 75 from the reservoir afforded by the rim 4 and chamber 6.

The bowl-construction thus described renders it economical in flushing water and the comparatively small amount thereof is thoroughly effective owing to the pressure at which it discharges into the bowl. More-over, the operation is wholly independent of any degree of pressure at which the flush-ing-water enters the chamber 6, the mech-a-nism being devoid of need of adjustment for adapting it to any degree of water-supply pressure; and the provision of the rear or overhead flush-tank being unnec-es-sary, though if already installed the bowl 80 may co-operate therewith, it may be dis-pensed with the resultant advantage of sav-ing in space and equipment.

I realize that considerable variation is possible in the details of construction herein 95 shown and described, and I do not intend to limit my invention thereto except as pointed out in the appended claims, in which it is my invention to claim all the novelty inherent in the invention as broadly 100 as permissible by the state of the art.

I claim:

1. A water-closet bowl having its back formed with a flush-water receiving reser-voir-chamber discharging directly into the 105 bowl through a valved opening and pro-vided with means of communication with a source of flush-water supply, a valve for

said discharge opening, and means actuated by pressure of water in the reservoir chamber for opening said valve.

2. A water-closet bowl having its back 5 formed with a flush-water receiving reservoir-chamber discharging through an opening therein directly into the bowl and provided with means of communication with a source of flush-water supply, a self-closing valve seating against said discharge-opening, a hollow rim surrounding the bowl, said rim communicating at its ends with said reservoir-chamber and forming a supplemental extension of the reservoir, and 10 means for locking the valve in closed position releasable by the pressure in said chamber of flush-water introduced therein.

3. A water-closet bowl provided with a rear flush-water receiving-chamber and a 20 hollow circumferential rim in open communication with each other and forming a reservoir, a self-closing valve seating at the discharge-opening in a wall of said chamber between the points of communication therewith of said rim, a locking device for 25 releasably securing the valve in its closed

position, and piston-operated means for unlocking said device by pressure against the piston of water introduced into said chamber for the flushing purpose.

4. A water-closet bowl provided with a rear flush-water receiving-chamber and a hollow circumferential rim in open communication with each other and forming a reservoir, a self-closing hinged valve seating at a discharge-opening in the forward 30 wall of said chamber between the points of communication therewith of said rim, a catch on the valve-seat and a dog on the valve releasably engaging the catch, a lever fulcrumed at one end in said chamber and extending at its opposite end to a notch in said catch for disengaging the dog therefrom, and a spring-pressed piston-device extending into the chamber and having a 35 link-connection with the lever for operating it to disengage the dog and unlock the valve by pressure against the piston of water introduced into said chamber for the 40 flushing purpose.

45 MICHAEL J. McANENY.
